UNITED STATES PATENT OFFICE.

THEODORE S. WILKIN, OF MILWAUKEE, WISCONSIN.

SAW-MILL SET-WORKS.

SPECIFICATION forming part of Letters Patent No. 335,168, dated February 2, 1886.

Application filed August 4, 1885. Serial No. 173,496. (No model.)

To all whom it may concern:

Be it known that I, THEODORE S. WILKIN, of Milwaukee, in the county of Milwaukee and State of Wisconsin, have invented certain new and useful Improvements in Saw-Mill Set-Works, of which the following is a specification.

My invention relates to saw-mill set-works, and is designed as an improvement upon the mechanism for which Letters Patent of the United States were granted to me bearing date the 3d day of March, 1885, and numbered 313,396.

In the aforesaid patent the knees were advanced and receded by fluid-pressure from a source outside of the carriages; but in the present apparatus the movements in both directions are effected by pneumatic pressure accumulated through the operation of a pump carried upon the carriage and operated through the travel thereof.

I may here remark that I am aware that the travel of the carriage has been utilized to compress air to recede the knees, and this I do not broadly claim; but, so far as I am aware, it is new to combine with a saw-mill carriage an air forcing or compressing apparatus operated through the travel of the carriage, and serving to provide the necessary power to both advance and recede the knees.

In the annexed drawings, Figure 1 is a perspective view of a saw-mill carriage provided with my improved mechanism; Fig. 2, a top plan view; Fig. 3, a side view, partly in section; Fig. 4, a cross-sectional view of the carriage; Fig. 5, a detail view.

A indicates the carriage, supported upon axles B, carried by wheels C, which travel upon rails, as usual. Upon the carriage are mounted head-blocks D, in which are arranged sliding knees E, having toothed rack-bars F at their under sides, connected either rigidly or otherwise with the knee, both arrangements being common and well known, and this matter being wholly outside of the present invention.

G indicates the set-shaft, which, as usual, is journaled in suitable boxes bolted to the framing of the carriage and furnished with a series of pinions, H—one to engage with and move each rack-bar F and its knee E.

Heretofore it has been customary to place

upon the set-shaft G a ratchet-wheel, and to provide pawl-and-lever mechanism by which to rotate the shaft, and thus to advance and recede the knees; but in the present instance such mechanism is not applied directly to the set-shaft. In lieu of the ordinary arrangement, I provide said shaft with a bevel-pinion, I, to which motion is given by a similar pinion, J, on a shaft, K, standing at right angles to shaft G, journaled in boxes on the frame of the carriage, and also provided with a pinion, L. Motion is given to pinion L by means of a toothed rack-bar, M, attached to or forming an extension of the rod of a piston, N, moving in a cylinder, O, to which air is admitted, preferably by a rotary four-way cock, P. A slide-valve may of course be used instead of the four-way cock; but the latter is deemed better for the purpose.

Q indicates an air-forcing pump or compressor, driven by suitable connection with a wheel or axle of the carriage, the drawings showing the piston-rod of the pump provided with a yoke, in which an eccentric, *a*, secured upon one of the axles B, works as the axle rotates. The pump forces air to cylinder O, either directly or, as is deemed advisable, through the medium of a compressed-air reservoir, R, provided with a check-valve, *b*, at the inlet-opening *c*, and with an escape or safety valve, *d*, which may be set to open at any desired pressure. Under this arrangement the travel of the carriage and consequent rotation of the axle B and its eccentric *a* causes the pump or air-compressor Q to supply air directly or indirectly, as above mentioned, to the cylinder O, which it enters on one or the other side of the piston, according to the position of the valve P, which is set and controlled by a hand-lever, S, in convenient position for operation by the sawyer. The air thus entering the cylinder and acting upon the piston forces the latter forward or backward, as the case may be, thereby moving the rack-bar, which rotates pinion L and its shaft K, and through the bevel-pinions I and J to set-shaft G, which causes the required movement of the knees.

As explained in my former patent above mentioned, it is impracticable to accurately control or regulate the movement of the knees through the valve alone, and for that reason I

again provide mechanism for controlling such movements, the power for producing the movement being supplied by the pneumatic apparatus. This mechanism is plainly shown in 5 Figs. 2 and 4, in which T indicates a worm-wheel keyed or made fast upon the set-shaft G, and U a screw or worm meshing with the worm-wheel T. The pitch of the worm-wheel is such that rotation cannot be imparted to 10 the worm from the worm-wheel so long as they are in mesh, and consequently the worm-wheel can only be rotated forward as permitted by the worm or screw, which is effected manually by the attendant and at such rate or to such 15 extent only as the setting of the knees demands.

To rotate the worm or screw as required, I employ a ratchet-wheel, V, keyed upon the shaft W, which carries the worm, and a hand-wheel, X, carrying reversible pawls Y, which may be made to engage with the ratchet-wheel V and to turn it either way required. The short horizontal shaft W is carried at its ends in boxes or bearings Z, connected by a light 25 open frame, A', the said frame A' being pivotally supported at the inner side of the carriage by an upright or bracket, B', secured to the longitudinal timbers of the carriage, as shown in Figs. 1, 2, and 4.

30 Projecting from the inside of the carriage is a bracket, C', in which is journaled an elbow-lever, D', whose upright arm D² is provided with a locking-dog, E, to engage with an arc, F', concentric with its pivot e. The lower 35 arm, D³, as shown in Fig. 4, extends parallel with and below the shaft W, and terminates beneath the end of the latter, the arm D³ being connected by a link, G', with the box Z at the free end of the shaft W. By rocking 40 the lever D' upon its pivot e the frame A' is tipped and the worm V thrown out of engagement with the worm-wheel T. When in this position, the pneumatic mechanism, operating through pinion I, shaft K, and pinions J I, 45 operates the shaft G and recedes the knees without being retarded or affected by the pawl-and-ratchet mechanism. This permits the knees to be receded quickly and without loss of time, which of course is a matter of importance.

With the apparatus thus constructed and arranged it will be seen that it is only necessary to cause the travel of the carriage over its track a sufficient number of times to accumulate a due pressure of air in the reservoir R, after which the knees will be moved as required by opening the cock or valve P and rotating the screw or worm U in the proper direction, the air-pressure effecting the required movements at a rate controlled by the rotation of the screw, the carriage coming to rest and being held against movement by the screw or worm whenever the latter ceases to turn.

65 In case of necessity the set-shaft may be rotated by the worm; but under ordinary circumstances this will not be done, the worm

being commonly used merely to regulate the movements of the knees.

It is of course feasible to operate the air-compressor by a separate wheel running along the track, or by a pinion meshing with a stationary rack-bar beneath the carriage and between the outside of the rail; but the plan illustrated is deemed best.

75 The same air-compressing mechanism can be made to operate the dogs carried by the knees.

I am aware that it is not broadly new to mount a cylinder upon a saw-mill carriage 80 and to force and compress air therein through the movements of the carriage to recede the knees.

Under my construction the movement of the carriage in either direction forces the air into 85 the cylinder and compresses it therein, and the air thus compressed serves not only to set the knees forward, but also to recede them. This has not been accomplished by any prior construction of which I am aware. In accomplishing this object I avoid the necessity 90 of having the knees set up manually, it being only necessary to allow the worm to turn (as controlled by the pawl-and-ratchet mechanism) slowly, and thus to control the setting of 95 the knees. A regulating or controlling device of substantially this nature is requisite, for if there were no such regulator the knees would be set too far forward by the air-compressor connections.

100 Having thus described my invention, what I claim is—

1. In combination with a saw-mill carriage, an air-compressor mounted wholly upon the carriage and bodily movable therewith, said compressor being adapted and arranged to be operated through or by reason of the travel 105 of the carriage and to furnish air to mechanism on the carriage.

2. In combination with a saw-mill carriage, 110 and with log-handling mechanism thereon, an air-compressor driven by connection with a truck of the carriage, a cylinder, a piston within said cylinder connected with the log mechanism of the carriage, and a valve between the air-compressor and the cylinder, to cause the air to enter upon either side of the piston at will.

3. In combination with a saw-mill carriage, 115 its knees and set-shaft, an air-compressor mounted wholly upon and operated by the travel of the carriage, a cylinder receiving air from the compressor, a piston within said cylinder, and intermediate connecting devices between the piston and the set-shaft, whereby 125 the travel of the carriage is caused to compress air, and the compressed air is in turn caused to actuate the set-shaft and move the knees.

4. The combination, substantially as described and shown, of carriage A, axles B, supporting said carriage, an eccentric, a, secured upon one of the axles B, an air-compressor, Q, carried by the carriage and oper-

ated by the eccentric *a*, a cylinder, *O*, receiving air from compressor *Q*, a valve, *P*, controlling the inlet and outlet of air to and from said cylinder, a piston, *N*, within said cylinder, a rack-bar, *M*, connected with said piston, a set-shaft, *G*, provided with pinions *H*, a series of sliding knees, *E*, mounted upon the carriage and having racks *F*, meshing with the set-shaft pinions, a shaft carrying a bevel-pinion, *J*, meshing with a like pinion, *I*, on the set-shaft, and a pinion, *L*, meshing with the rack-bar *M*, a worm-wheel, *T*, keyed fast upon the set-shaft, a worm, *U*, meshing with said worm-wheel, and a lever for rotating the worm.

5 5. In combination with a saw-mill carriage and its sliding knees, and an air-compressor mounted upon and operated through the travel of the carriage, a cylinder receiving air therefrom, a piston within said cylinder connected through intermediate gearing with the set-shaft, a worm-wheel mounted upon the set-shaft, and a worm meshing with said worm-wheel and serving to regulate or control its 20 rotation.

25 6. In combination with the set-shaft of a saw-mill carriage, and with mechanism for rotating said shaft, a worm-wheel secured

upon said shaft, and a worm meshing with the worm-wheel, and adapted to be rotated 30 manually to permit and control the rotation of the set-shaft.

7. In combination with a saw-mill carriage and its sliding knees, and an air-compressor mounted upon and operated through the 35 travel of the carriage, a cylinder receiving air therefrom, a piston within said cylinder connected with the set-shaft, a worm-wheel mounted on the latter, and a worm meshing with said worm-wheel and adapted to be disengaged 40 therefrom at will.

8. In combination with the set-shaft of a saw-mill carriage, and with mechanism for rotating said shaft, a worm-wheel secured upon said shaft, a worm meshing with the 45 worm-wheel adapted to be rotated manually to permit and control the rotation of the set-shaft, a pivotal box or bearing for said worm-shaft, a hand-lever journaled upon the frame, and a link connecting the hand-lever and the 50 free end of the worm-shaft.
